Design U.S. Appl. No. 29/668,464, filed Oct. 30, 2018, entitled "Oral Irrigator".

(Continued)

Primary Examiner — Lilyana Bekic(74) *Attorney, Agent, or Firm* — Dorsey & Whitney LLP(57) **CLAIM**

We claim the ornamental design for an oral irrigator, as shown and described.

DESCRIPTION

FIG. 1 is a front isometric view of an oral irrigator.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

The broken lines illustrate portions of the oral irrigator that form no part of the claimed design.
